CLAIM

The ornamental design for a set of strategy game boards, as shown and described.

DESCRIPTION

FIG. 1 is a front view of the set of strategy game boards; FIG. 2 is a rear view of the set of strategy game boards; FIG. 3 is a front view of the set of strategy game boards; and, FIG. 4 is a rear view of the set of strategy game boards. The boards are of conventional thickness and the sides are unornamented and form no part of the claimed design.
